UNITED STATES PATENT OFFICE.

MORRIS CRAMER, OF CLEVELAND, OHIO.

DIESTOCK.

1,397,243.

Specification of Letters Patent. Patented Nov. 15, 1921.

Application filed March 18, 1920. Serial No. 365,461.

To all whom it may concern:

Be it known that I, MORRIS CRAMER, a citizen of the United States, residing at Cleveland, in the county of Cuyahoga and 5 State of Ohio, have invented a certain new and useful Improvement in Diestocks, of which the following is a full, clear, and exact description, reference being had to the accompanying drawings.

10 The object of this invention is to provide a very simple, efficient and compact multiple die stock adapted for use of plumbers, gas fitters, steam fitters, etc. It provides means whereby with one tool a number of sizes of 15 pipes may be threaded without any change in the tool or dies. A more specific object of this invention is to so arrange the die stock that it may be constructed of a single integral frame, carrying the dies and guide 20 bushing therefor, in a substantially medial plane with relation to the handles of the stock. Other objects include convenience of replacement of the dies, and accessibility for adjustment thereof. 25 In the drawings, Figure 1 is a side elevation of my die stock, Fig. 2 is an end elevation, that is looking toward the die stock along one of its handles, Fig. 3 is a trans- 30 verse section taken substantially along the plane extending through the handles, while Fig. 4 is a central section at right angles to Fig. 3.

35 My invention readily adapts itself for a die stock carrying four sizes of dies and such is the construction shown in the drawings, in which the frame of the die stock designated 1 comprises a single casting, somewhat globular in shape and having equally spaced outwardly projecting bosses for the guiding 40 bushings, and having bosses at right angles thereto for the handles, producing in general a shape corresponding to a jackstone.

45 The casting is made hollow for the most part while it is provided with ways or seats 5, comprising flat members supporting the inner sides of the dies 10. The sides of the dies are guided by parallel surfaces or ribs 6. Extending outwardly from these ribs 6, are surfaces forming the sides of openings 8, 50 between the supports 9 for the annular sockets 11 into which the guide bushings 15 are removably fitted. The members 9 and 11 form the outwardly projecting bosses and as stated are so cut away as to leave openings 8, which it will be seen from the in-

spection of Figs. 1 and 2 admit the dies for placing them in position and removing them.

The dies are in the usual construction, having openings through which securing screws 20 may extend, the openings being 60 elongated to allow for adjustment by means of screws such as indicated at 22. The screws 22 extend through bosses 23 projecting outwardly from the substantially circular bosses 25, the central portions of which 65 are threaded to receive the handles 30. The interior of the casting is cored out as much as possible commensurate with the desired strength. For example, squared cavities occur within the supports 5, at the inner ends 70 of the handles. These cavities open into an enlarged cavity into which the ends of the dies project, and surrounding this cavity, which opens outwardly at 8 as described, are walls of a thickness sufficient only to 75 provide rigid support and connections between the die supports and the guide bushings. This construction is apparent from the sectional view of Fig. 4.

80 From the foregoing, it will be seen, that I have provided a die stock frame which may conveniently carry four or more sets of dies in guide-ways substantially parallel with the handles, whereby they may operate 85 upon a pipe whose axis lies in a medial plane with relation to the die stock handles; and that the guide bushings for each set of dies being outside of and closely adjacent to the dies, allows the threading of comparatively short lengths of pipe. It will further be 90 seen that the die stock is self-contained, neat in appearance and that its projections, namely the bosses, are so arranged as to protect the dies and screws, whereby practically no harm may result from rough handling or dropping the die stock. It is comparatively light and yet very rigid and durable. 95

Having thus described my invention, I claim:

100 1. In a die stock, the combination of a hollow integral frame, alined handles carried by the ends of the frame, a plurality of sets of dies and guiding bushings therefor, arranged in a medial plane with relation to the handle, the frame having carrier bosses for the bushings arranged to position each bushing outside of its set of dies. 105

2. In a die stock, the combination of a hollow frame, alined bosses for receiving 11

handles, a plurality of guides substantially parallel with the handles and at each side of a medial plane, means for adjustably securing the dies in the said guides, the frame 5 having walls connecting said guides and projecting outwardly, hollow bosses with which said outwardly projecting walls merge, said bosses being each arranged to carry a guide bushing in alinement with a set of dies, the 10 outward projecting portions being so separated as to admit the dies being placed in position from the exterior of the frame.

3. In a die stock, the combination of the frame comprising end bosses, a plurality of 15 guide-ways formed on the sides of said bosses, walls connecting said bosses and extending outwardly at each side of the guideways, bushings carried by the outwardly extending portions, said portions being separated, leaving space to allow placing the 20 dies in position from the exterior of the frame, and handles carried by the end bosses.

4. In a die stock, the combination of an 25 integral hollow frame comprising bosses at opposite ends for receiving the handles, guide-ways having a plurality of sets of dies equally spaced about said bosses and substantially parallel with the handles whereby the ends of the dies project inwardly therefrom, hollow bosses having 30 guide bushings for each set of dies, walls connecting said end bosses and hollow bosses, said walls having substantially a spherical form and curving and merging into the respective bosses and leaving openings outwardly from the guide-ways to admit the 35 dies from the exterior of the frame.

5. In a die stock, the combination of a 40 hollow integral frame consisting of alined handle bosses, guide-ways on the outer surfaces of said bosses and each adapted to re-

ceive one of a pair of dies whereby a plurality of dies may be carried in alinement with their ends projecting inwardly past guideways to an operative position, walls connecting 45 said bosses and extending outwardly over said dies, hollow rings on the outwardly projecting portions of the walls, each adapted to carry a bushing outside of and in alinement with a set of dies, said 50 outwardly projecting portions being sufficiently separated as to leave an opening allowing the dies to be placed in position from the exterior of the die stock.

6. In a die stock, the combination of a 55 frame, comprising end bosses, a plurality of guideways on the sides of said bosses, walls connecting said bosses and extending outwardly at each side of the guideways, bushings carried by the outwardly extended portions, said portions being separated to leave 60 space to allow placing of the dies in position from the exterior of the frame, and to leave openings adjacent said dies to allow escape of the cuttings.

7. In a die stock, the combination of a 65 frame, comprising end bosses, a plurality of guideways therefor on the sides of said bosses, walls connecting said bosses and extending outwardly at each side of the guideways and uniting medially of said guideways to form work guiding bosses.

8. In a die stock, the combination of a 70 frame, comprising end bosses, a plurality of guideways formed on the sides of said bosses, walls connecting said bosses and arching said guideways to form work holding bosses and openings adjacent said guideways.

In testimony whereof I hereunto affix my signature.

MORRIS CRAMER.
